EXPLOSIVELY ACTUATED TOOL FOR MAKING ELECTRIC POWER CONNECTIONS

William F. Broske, Camp Hill, and Frederick William Wahl, Middletown, Pa., assignors to AMP Incorporated, Harrisburg, Pa.

Filed Jan. 30, 1964, Ser. No. 78,428

Term of patent 14 years

(Cl. D54—13)

FIGURE 1 is a perspective view of an explosively actuated tool for making electric power connections embodying the new design;

FIGURE 2 is a side view of the tool of FIGURE 1;

FIGURE 3 is a top plan view of the tool; and

FIGURE 4 is a front end view of the tool.

The undisclosed side is substantially the same in appearance as the side shown.

We claim:

The ornamental design for an explosively actuated tool for making electric power connections, substantially as shown and described.
